MOBILE RADIO ANTENNA OR THE LIKE

James W. Shirey, Lakeland, Mich., assignor to L-Coil
Research, Brighton, Mich., a partnership of Michigan

Filed Oct. 9, 1967, Ser. No. 8,914

Term of patent 14 years

U.S. Cl. D14—6
Int. Cl. D12—14

FIG. 1 is a perspective view of a mobile radio antenna, or the like, showing my new design;

FIG. 2 is an elevational view thereof; and

FIG. 3 is a top view thereof.

The automobile shown in broken lines is included for illustrative purpose only, and the dominant features of my design reside in the portions shown in full lines.

I claim:

The ornamental design for a mobile radio antenna or the like, as shown and described.
